UNITED STATES PATENT OFFICE.

HARRY ANDREW WRIGHT, OF SPRINGFIELD, MASSACHUSETTS, ASSIGNOR
TO THE YOST ELECTRIC MANUFACTURING COMPANY, OF TOLEDO,
OHIO, A CORPORATION.

SHADE-HOLDER FOR INCANDESCENT ELECTRIC LAMPS.

No. 815,245.

Specification of Letters Patent.

Patented March 13, 1906.

Application filed July 9, 1904. Serial No. 215,857.

To all whom it may concern:

Be it known that I, HARRY ANDREW WRIGHT, a citizen of the United States of America, residing at Springfield, in the county of Hampden and State of Massachusetts, have invented new and useful Improvements in Shade-Holders for Incandescent Electric Lamps, of which the following is a specification.

10 This invention relates to shade-holders; and it is particularly adapted to incandescent electric lamps, the object of the invention being to provide a holder adapted to be removably secured to the sockets of the lamps, provision being made to adapt the holder to sockets having different diameters.

15 The invention consists in the construction described in the following specification and pointed out clearly in the claims forming a part thereof.

20 In the drawings accompanying this specification, Figure 1 is an elevation of an incandescent lamp and socket, showing the shade secured thereto, certain of the parts being shown in section. Fig. 2 is a perspective view of the shade-holder, the shade being removed. Fig. 3 is a plan view of a shade-holder.

25 In carrying out this invention the shade-holder is made of one piece of wire and is provided with two rings, approximately concentric, one located above the other, the ring *a* being the clamping-ring whereby the holder is secured to the socket by constriction, and the ring *b* is that which fits within the conical shade *c* somewhat below the upper end thereof, whereby the shade, as shown in Fig. 1, may be supported on this ring out of contact with the lamp or socket. The ring *a* is made

30 with two outwardly-extending arms *d* and *d'*, lying in the plane of the ring and being, as shown in Fig. 3, approximately radial to the center thereof. The arm *d'* being one end of the wire, has its extremity bent downwardly at right angles to the plane of the ring *a* and backwardly under the arm to provide a good bearing for the fingers when the arms are pressed together. As far as utility is concerned the wire might terminate at the end of the arm *d'* and the device still be entirely operative.

35 After forming the ring *a* and the arm *d* the outer end of the latter is curved downwardly

and backwardly to conform to the shape of the end of the arm *d'* (and for the same purpose) 55 and then runs downwardly, as at *e*, to the plane of the ring *b*, which is then formed, as shown in the drawings, parallel and substantially concentric with the ring *a*. The opposite end of the wire (of which the ring *b* is formed) terminates substantially at the base of the perpendicular portion *e*. This portion *e* of the shade-holder lies substantially in the plane of the side of the shade *c*.

40 On the ring *b* there are located several flat 65 metal clips *f*, having a swinging movement on the ring, the upper hook-shaped ends *g* of which are bent over the upper edge of the shade, as shown in Fig. 1, in such manner that the shade can have no vertical movement relative to the ring *b*, the hooks preventing upward movement and the ring *b*, which is of larger diameter than the open end of the top of the shade, preventing downward movement of the latter. The shade 70 may be made of paper, metal, or other suitable material, as the holder is adapted to be secured to a shade of any material. 75

45 On one of the arms, as *d*, is a swinging hook *h*, which may be made of flat metal or wire, the hook end *j* thereof being arranged to snap over the arm *d'* to hold the ring *a* in constricting position around the lower end of the lamp-socket *m*. When the hook *h* is swung back, leaving the arms *d* *d'* free, the ring *a* will 85 spring open wide enough to receive a lamp-socket, and the two ends of the arms *d* *d'* may then be pressed together and the hook *h* swung over to engage said arm to clamp the shade-holder to the socket. By sliding the 90 hook *h* outwardly on the arms it will be seen that the ring *a* may be constricted to a greater degree than if the hook were located close to the ring, owing to the radial spread of these arms, thus adapting the device to be clamped 95 to sockets whose diameters may differ more or less.

50 In applying the shade to the shade-holder the latter is passed up into the shade and the ring *a* and the arms *d* *d'* passed through the open end thereof to bring the ring *b* to a bearing against the inside of the shade, and the clips *f*, which when attached to the ring *b* are left flat, are then bent over the upper edge of the shade to form the hook ends *g*, which lock 100 the shade to said ring. 105

It is seen from the description of this device that it may be very cheaply made and does away with staples and the like whereby the shades are usually secured to the holders and permits the use of the holder on a shade made of any material.

Having thus described my invention, what I claim, and desire to secure by Letters Patent of the United States, is—

- 10 1. A shade-holding clamp comprising two open rings in different planes and of different diameters, the smaller of the rings having two outwardly-extending finger-pieces, one of the finger-pieces constituting one of the ends of the clamp, the other of the finger-pieces extending downward from the smaller ring and integral with the lower open ring, the other end of the clamp terminating in close proximity to the downward-bent portion of the finger-piece.
- 15 2. A shade-holder for incandescent electric lamps consisting of an open ring to receive a lamp-socket and a shade-holding ring of greater diameter than said open ring and lo-

cated in a lower parallel plane, said two rings 25 being formed of one piece of metal, said open ring having ends extending outwardly therefrom one of which is bent downwardly to connect with the shade-holding ring, together with a device to secure the outwardly-extending 30 ends of said open ring together to constrictively engage the socket of a lamp.

3. A shade-holder for incandescent electric lamps consisting of an open socket-engaging ring and a shade-holding ring of larger diameter and supported below, and parallel with the open ring, said two rings being formed of one piece of wire, and said open ring having outwardly-extending ends one of which is bent downward to connect with the shade-holding ring combined with a hook slidably mounted on one of the outwardly-extending 40 ends of the open ring to engage the other end.

HARRY ANDREW WRIGHT.
